UNITED STATES PATENT OFFICE

2,505,169

JEWELRY CHAIN WITH INTEGRAL PINS

Jonas Bikoff, Brooklyn, N. Y.

Application April 1, 1946, Serial No. 658,837

6 Claims. (Cl. 59—80)

1

This invention relates to flexible, flat, broad jewelry chains, particularly for bracelets, and has for its main object to provide a chain of this character which will be composed of identical links pivotally secured to one another in a uniform and novel manner, whereby uniform, simple, quick and inexpensive manufacturing and assembling will be made possible, and to eliminate need for two differently shaped links for bracelets of this type.

Another object of this invention is to provide a jewelry chain of the mentioned character, in which no separate pins are used, but the pivot pin between the links of the chain will be integral with, and part of, the links themselves, whereby extra labor, complications in manufacturing and use, will be avoided.

Other objects of this invention will be apparent as the specification of the same proceeds, and among others, I may mention to eliminate the need of having two differently shaped links, as has been the case with bracelets of this type heretofore.

In the drawings forming a part of this specification and accompanying the same:

Fig. 1 is a plan view of a portion of a chain constructed according to my invention;

Fig. 2 shows the blank of a link in said chain;

Fig. 3 is an end view and indicates the way said blank is bent when the chain is being manufactured, the view being taken as indicated by arrow 3 in Fig. 4;

Fig. 4 is a sectional view, the section being taken on the line 4—4 of Fig. 3;

Fig. 5 is a side view of a portion of the assembled chain, the last four figures being on a larger scale than Fig. 1.

Referring now to the drawings more in detail by characters of reference, the numeral 10 indicates the blank of a link in my chain, in general, and the same will be made of a piece of flexible but shape retaining sheet material, like metal, and it will have a body portion 11, arms 12 at one side thereof, and arms 13 at the other side, the two arms being alternately spaced, having the respective spaces 14 and 15 between them.

A portion 16 of the material of the blank between the arms 12 will be left intact forming a bridging piece between the arms 12, which ultimately will be used as the pivot pins for the chain.

Arms 13 will be bent doubled in a spaced apart manner, generally intermediate their ends, as indicated by the dotted lines 17, and similarly arms 12 will be bent doubled in the same direction as arms 13 on the dotted line 18, which preferably

may run at about the center of the bridging pin portions 16. A view of the blank so bent is shown in Fig. 3 and a section thereof in Fig. 4.

In forming the chain, the hook formed by the doubling, in a spaced apart manner, of the arm 13, will be made to embrace the pin portion 16 of the adjacent link, as indicated in Fig. 5 and shown in a plan view in Fig. 1.

In this manner the jewelry chain may be formed with very closely fitting portions in its design and of a very simple construction.

I also prefer to have the pin forming portions 16 be of considerable width and provide partial transverse separation lines or incisions 19 at the ends of their sides 20, so that upon forming the links their separated portions may be bent more inwardly than the arms 12 as indicated in Figs. 4 and 5, said more inwardly bent portions 20 engaging arms 13 of the adjacent link and thereby causing the links to be drawn closer to another, (Fig. 5).

While I have shown a preferred embodiment of my invention, it is to be understood that changes and variations may be resorted to in the elements, construction and combination of my invention, and I reserve my rights to such changes, variations and uses, as are within the spirit of this specification, and the scope of the claims hereunto appended.

30 What I claim as new and want to protect by Letters Patent of the United States, is:

1. In a jewelry chain composed of a plurality of links of sheet material, each link having a body portion in the plane of the chain but transversely to the longitudinal axis of the chain, and alternately placed arms projecting from opposite sides of each link, the combination therewith, of individual comparatively short pins secured between each pair of arms on one side of each link, 35 the end portions of the arms on each side being bent doubled but in a spaced apart manner on the same side of the plane of the chain, and the hooks so formed by the bending of the pinless arms in one link being placed to pivotally embrace the pins between the respective arms in the adjacent link.

2. In a jewelry chain, composed of a plurality of links of sheet material, each link having a body portion in the plane of the chain but transversely to the longitudinal axis of the chain, and alternately placed arms projecting from opposite sides of each link, the combination therewith, of individual comparatively short pins secured between each pair of arms on one side of each link, 50 the end portions of the arms on each side being

bent doubled but in a spaced apart manner on the same side of the plane of the chain, and the hooks so formed by the bending of the pinless arms in one link being placed to pivotally embrace the pins between the respective arms in the adjacent link, each link being formed of one integral piece of sheet material including said pins.

3. In a jewelry chain, composed of a plurality of links of sheet material, each link having a body portion in the plane of the chain but transversely to the longitudinal axis of the chain, and alternately placed arms projecting from opposite sides of each link, the combination therewith, of individual comparatively short pins secured between each pair of arms on one side of each link, the end portions of the arms on each side being bent doubled but in a spaced apart manner on the same side of the plane of the chain, and the hooks so formed by the bending of the pinless arms in one link being placed to pivotally embrace the pins between the respective arms in the adjacent link, the arms and the pins between them being bent doubled substantially on the center line of said pins.

4. In a jewelry chain, as set forth in claim 1, said pins being flat, substantially wide plate portions, the arms at their sides and the pins themselves being bent on about the center lines of the pins.

5. In a jewelry chain, as set forth in claim 1, said pins being flat, substantially wide plate portions, the arms at their sides and the pins themselves being bent on about the center lines of the pins, a portion of the plate pins being separated and bent inwardly on a sharper curve than the arms on their side whereby said inwardly bent portion will engage the bent pinless arms of the adjacent link in the chain and draw said two links closer to one another.

6. In a jewelry chain, as set forth in claim 1, said pins being flat, substantially wide plate portions, the arms at their sides and the pins themselves being bent on about the center lines of the pins, said plate pins being an integral part of the sheet material from which the blank for the link is formed.

JONAS BIKOFF.
